UNITED STATES PATENT OFFICE.

JOHN W. JACKSON, OF SPRINGFIELD, ILLINOIS.

PLUNGER-OPERATING MEANS FOR WASHING-MACHINES.

1,151,362.

Specification of Letters Patent. Patented Aug. 24, 1915.

Continuation of application Serial No. 735,210, filed December 6, 1912. This application filed May 21, 1914. Serial No. 839,993.

To all whom it may concern:

Be it known that I, JOHN W. JACKSON, a citizen of the United States, and residing at Springfield, in the county of Sangamon and 5 State of Illinois, have invented certain new and useful Improvements in Plunger-Operating Means for Washing-Machines, of which the following is a specification.

This invention relates to washing machines, and more particularly, to plunger operating mechanism therefor.

This application is a continuation of my co-pending application, Serial No. 735,210, filed December 6, 1912, as to subject matter, 15 which is common to the two applications.

The objects of this invention are, to provide plunger operating mechanism for washing machines, which is simple in construction, cheap to manufacture, simple, effective, 20 and easy in its operation, and which is not liable to get out of repair.

Further objects will appear from the detail description taken in connection with the accompanying drawing, in which:

25 Figure 1 is a vertical section through a washing machine container, showing the plunger operating mechanism in elevation, Fig. 2 is a section on the line 2—2, Fig. 1, showing the mechanism in elevation, Fig. 3 is a section on the line 3—3, Fig. 1, and, Fig. 4 is a detail section on the line 4—4, Fig. 1.

Referring to the accompanying drawing, 10 designates a container adapted to receive water and the clothes to be washed, provided 35 with a cover 11 and a suitable plunger 12, as described in the application referred to. The plunger 12 has a plunger rod 13 guided by a bearing sleeve 14 secured to and projecting from the under side of the cover.

40 A bracket 15 of U-shaped form has spaced legs or uprights 16 and 17, provided with feet 18 resting on the cover 11 and secured thereto by bolts 19. The yoke of this bracket is provided with a boss 20 which supports 45 and guides the end of the plunger rod projecting through the cover.

50 A bearing bracket 25 is mounted on the cover near its edge, and supports one end of a drive shaft 26, the other end of which is supported by a boss 27 on the upright 17. One end of the shaft is provided with a crank 28, and the other end has fixed thereto a large gear 29, meshing with a pinion 30, fixed to a shaft 31, mounted in a boss 32 on 55 the upright 17 and held against endwise

movement by nuts 33. A crank 34, fixed to the shaft 31 and the pinion 30, has a crank pin 35 connected to one end of a pitman 36, the other end of which is connected, by a wrist pin 37, with the sleeve 38 slidably 60 mounted on the plunger rod 13. Sleeves 39 and 40 are rigidly connected together by a yoke 41, and these sleeves are positioned on opposite sides of the sleeve 38 and spaced therefrom. The sleeve 40 is split, as shown 65 at 42, and the split lugs 43 are connected by a clamping bolt 44. By means of this construction, both sleeves can be clamped to the shaft as a unit. Springs 45 are positioned between the sleeves 38, 39 and 40. The 70 plunger rod 13 has a handle 50 at its upper end, whereby the plunger may be raised and lowered, and a set screw 51 is provided for clamping the plunger in any desired position. Rotation of the shaft 26, through the 75 crank 28, will cause reciprocation of the plunger. In view of the ratio of the gears 29 and 30, a single rotation of the shaft 26 will cause a plurality of reciprocations of 80 the plunger. Now, it is found, in practice, that, if the sleeve 38 is rigidly connected to the plunger, there are certain points in the revolution of the shaft, especially at the point where the crank 28 is raised, where the leverage of the operator's arm is not 85 sufficient to conveniently and easily move the plunger, as this plunger comes down on the clothes. It is for this purpose that the yielding connection between the crank and the plunger is provided. During the point 90 in the rotation of the crank to which I have referred, and which we may call the dead center with respect to the operator, and as the plunger moves down on the clothes, the lower spring 45 will yield so as to permit the 95 crank to be turned over the dead center. It has been found by actual experience that this will accomplish the result desired. Moreover, the presence of these springs secures an efficient and easy operation. The 100 sleeves can be clamped in any adjusted position by the adjustment of a single screw 44, as these sleeves will move as a unit and carry the sleeve 38 with them. The plunger can be locked in any desired position vertically by the set screw 51, which is often desired where the cover has to be opened. By guiding the plunger rod both by a bearing on the cover and a yoke on the bracket, no 105 side strain is thrown on the plunger rod, 110

and easy operation is obtained. In view of the fact that the bracket must be connected with the sheet metal cover, where a stress is liable to tear out the rivets or bolts, the bracket is of U-shaped construction so as to divide and equalize the strain.

It is obvious that various changes may be made in details of construction without departing from the spirit of this invention, and it is, therefore, to be understood that this invention is not to be limited to the specific construction shown and described.

Having thus described the invention, what is claimed is:

15. 1. Plunger operating means for washing machines, comprising a support, a bracket mounted on said support and having a yoke, a plunger rod projecting through said support and guided in said yoke, driving mechanism detachably connected to reciprocate said plunger rod and mounted on said bracket, and means for clamping said plunger in said yoke to fix the plunger against movement.
20. 2. Plunger operating means for washing machines comprising a support, a plunger rod sustained thereon, a driven shaft mounted on the support and having a crank, means

yieldably connecting said crank with the plunger rod for reciprocating the latter, a 30 drive shaft, and operative connections between the drive shaft and driven shaft.

3. Plunger operating means for washing machines comprising a support, a plunger rod mounted in guides on the support, a 35 driven shaft mounted on the support and provided with a crank, a movable bearing on the plunger rod engaged with said crank, springs yieldably sustaining said bearing, and means for operating the driven shaft. 40

4. Plunger operating means for washing machines, comprising, a bracket, a plunger rod guided by said bracket, spaced sleeves on said plunger rod, a yoke connecting said sleeves, means for connecting said sleeves with said plunger rod, a sleeve loose on said plunger rod and positioned between said first sleeves, springs between said sleeves, and a crank connected to reciprocate said loose sleeves. 45 50

In testimony whereof I affix my signature in the presence of these two witnesses.

JOHN W. JACKSON.
